UNITED STATES PATENT OFFICE

2,320,503

HIGH-PRESSURE STEAM GENERATOR

John Phillips Badenhausen, Philadelphia, Pa.

Application January 8, 1942, Serial No. 425,953

7 Claims. (Cl. 122—235)

This invention relates to high pressure steam generators, and more particularly to a high pressure steam generator in which the necessity for any drums is eliminated.

It is the principal object of the present invention to provide a steam generator for operation at very high pressures and which is simple in its construction and compact in its arrangement.

It is a further object of the present invention to provide a steam generator for operation at very high pressures and with adequate provisions for circulating the fluid within the steam generator.

It is a further object of the present invention to provide a steam generator for operation at very high pressures and in which a portion of the energy in the steam is utilized for maintaining circulation of the fluid within the steam generator.

It is a further object of the present invention to provide a steam generator for operation at very high pressures and in which the rate of circulation of the fluid within the steam generator is or may be increased with increase in the steam output.

Other objects of the invention will be apparent from the annexed specification and claims.

The nature and characteristic features of the invention will be more readily understood from the following description, taken in connection with the accompanying drawings forming part hereof, in which:

Figure 1 is a vertical central sectional view through a preferred embodiment of the steam generator of the present invention, and taken approximately on the line 1—1 of Fig. 2;

Fig. 2 is a horizontal sectional view taken approximately on the line 2—2 of Fig. 1;

Fig. 3 is an enlarged detail view showing a preferred form of circulator; and

Fig. 4 is a view showing a modified form or circulator.

It will, of course, be understood that the description and drawings herein are illustrative merely, and that various modifications and changes may be made in the structure disclosed without departing from the spirit of the invention.

The steam generator of the present invention is particularly intended for use with very high pressure steam, at pressures in excess of 1,000 lbs. per square inch, and to and beyond pressures of 3,000 lbs. per square inch, and a steam generator is provided which does not require any drums for the water or for the steam and water. Adequate

provision is also made for circulating the water within the steam generator.

Referring more particularly to the drawings, in the preferred embodiment of the steam generator 5 of the present invention therein illustrated, a horizontal top wall 10 is provided together with vertical side walls 11 and 12, a vertical front wall 13 and a horizontal bottom wall 14. Spaced from and parallel to the front wall 13, a downwardly extending baffle 15 is provided, the lower end of the baffle 15 being spaced from the bottom wall 14 to permit gas flow therearound. The baffle 15 provides, with the forward portions of the top wall 10, the side walls 11 and 12, and the bottom wall 14 and with the front wall 13, a combustion space 16.

Suitable burners 17 are provided in the top wall 10 for down firing of pulverized coal, oil, or other suitable fuel, with air, for combustion within the 15 combustion space 16.

At the lower part of the front wall 13, a lower horizontal header 20 is provided and, at the upper part of the front wall 13, an upper horizontal header 21 is provided. A bank of steam generating riser tubes 22 extends from the lower header 20 to the upper header 21, and lines the front wall 13.

The side walls 11 and 12 are each provided with lower horizontal side wall headers 23 and upper horizontal side wall headers 24. Banks of steam generating riser tubes 25 connect the respective lower and upper headers 23 and 24, and line the respective side walls 11 and 12.

A plurality of vertically disposed header elements 30 are employed, and are spaced to the rear of the baffle 15 a sufficient distance to provide an upward pass for the gases from the combustion space 16. To the rear of the vertical header elements 30, a wall or baffle 31 is provided which extends upwardly from the bottom wall 14 and the upper end of which is spaced downwardly from the top wall 10 to permit the flow of gases of combustion thereover. The vertical header elements 30 are arranged substantially parallel along the wall or baffle 31 and in spaced relationship between the side wall 11 and the side wall 12, and preferably extend upwardly from the bottom wall 14 and through and beyond the top wall 10 for purposes hereinafter explained. Removable closures 32 are mounted on the upper ends of each of the vertical header elements 30, through which access to the interior may be had.

The upper front header 21 is connected to the vertical header elements 30 by steam generating

tubes 33 which line the top wall 10, and which are shaped where necessary to avoid any interference with the burners 17.

A bank of steam generating tubes 34 is provided at the upper portion of each side wall 11 and 12 for connecting the upper side wall headers 24 to the vertical header elements 30 at each side for the delivery of fluid thereto.

The vertical header elements 30 are connected to the lower side wall headers 23 by banks of tubes 35 for the delivery of water from the vertical header elements 30 to the lower side wall headers 23. The vertical header elements 30 are also respectively connected by a bank of tubes 36 along the bottom wall 14 to the lower front wall header 20 for the delivery of water thereto.

In the space between the rear baffle 15 of the combustion chamber 16 and the upwardly extending wall or baffle 31, groups of steam generating tubes 35 are provided for each vertical header element 30. These groups of tubes 35 preferably consist of bent tubes extending at predetermined levels toward the baffle and then upwardly within the space, and then at other predetermined levels extend into communication with the interior of the vertical header elements 30. While the tubes of the groups of steam generating tubes 35 may be disposed in any desired manner, the tubes 35^a which are connected at the lowermost level of connection to the vertical header elements 30 and at the uppermost level to the vertical header elements 30 are preferably disposed over their vertical extent closest to the baffle 15. The tubes 35^b connected to the vertical header elements 30 at the next higher level of connection at the bottom and the next lower level of connection at the top are preferably spaced rearwardly from the baffle 15 and the tubes 35^a, the same rearwardly spaced arrangement being followed for each respective level of connection to the vertical header elements 30. The tubes 35 at each level extend outwardly from the header elements 30 in a manner to permit of proper connection to the vertical header elements 30, and also to secure the proper disposition of the tubes 35 within the upward pass.

The upper ends of the vertical header elements 30 are connected by suitable pipes 36 to a superheater header 37 from which header superheater tubes 38 extend downwardly and then upwardly within the upward pass, the superheater tubes 38 also being connected to a superheater header 39 from which the superheated steam is withdrawn.

While the steam generator, as heretofore described, may be satisfactory for relatively low pressures, for pressures of the range in which the steam generator is intended to operate provision is made for positively circulating the fluid within the steam generator. The water is forced downwardly within the vertical header elements 30, and for this purpose each vertical header element 30 is preferably provided with a circulator of any desired construction, but preferably of a relatively simple character to avoid the necessity for adjustment or for repairs.

One form of circulator is shown in Figs. 1 and 3 and is preferably carried by the closure 32 and removable therewith as a unit. The circulator preferably includes a sleeve 60 secured to the upper closure 32 and capable of insertion into and removal from the vertical header elements 30 for repair and for replacement. A

prime mover, such as a turbine or motor, is mounted and supported by each sleeve 60. Each sleeve 60 preferably has an opening 61 therein to permit the discharge of steam from the interior of the sleeve 60 to the superheater connection pipe 36, and also preferably has an opening 62 to permit the discharge, into the interior of the sleeve 60, of steam from the tubes 33, 34 and 35. The prime movers preferably include stator and rotor portions 40 and 41 mounted above the uppermost level of connection of the tubes 33, 34 and 35, and below the superheater connection pipes 36, the stator portions 40 being secured to the sleeve 60, and the rotor portions 41 being connected to shafts 42 mounted in suitable bearing supports 43, carried by each sleeve 60, and bearing supports 43^a carried by each closure 32.

At the lower end of the shafts 42, pumps 44 are provided so that upon operation of the prime movers 40, 41, the pumps 44 are driven by the shafts 42 for forcing the water downwardly within the vertical header elements 30.

It will be noted that the effective pumping action of the pumps 44 will be determined by the volume of steam passing through the prime movers 40, 41, to the superheater so that as the demand for steam is increased the positive circulating action of the water in the steam generator will also be increased.

In the form of the invention shown in Fig. 4, a different form of circulator is employed and is located at the lower portions of each of the vertical header elements 30. The circulators include prime movers 45 of any desired type, such for example, as controllable speed electric motors, for driving shafts 46 supported in bearings 47 and extending upwardly within the vertical headers 30. Pumps 44 are mounted on the upper ends of the shafts 46 for effecting positive downward circulation of the water within the vertical header elements 30, in accordance with the speed of rotation of the motors 45 as determined by the steam demand.

The steam generator may also include, as an integral part thereof, an economizer 50 for receiving the gases discharged from the boiler section and over the upper end of the wall or baffle 31, and is disposed in a downward pass between the wall or baffle 31 and a wall or baffle 51. The economizer 50 is connected by pipes 52 to the vertical header elements 30 for the delivery of heated water thereto.

An air preheater 53 may also be provided for receiving the exhaust combustion gases from the economizer 50 for preheating the air, introduced with the fuel, for combustion.

The mode of operation will, it is thought, be apparent from the foregoing. It may, however, be noted that the fuel introduced downwardly through the burners 17 into the combustion space 16 burns therein, and the heat released by the combustion is effective for generating steam in the tubes lining the walls of the combustion space. These tubes include the banks of tubes 22 on the front wall and the banks of tubes 25 on the side walls. The gases of combustion pass downwardly within the combustion space 16 and around the lower end of the wall or baffle 15 and upwardly in the upward pass where further quantities of heat are given up to the tubes 35, to the superheater tubes 38, and to the vertical header elements 30. The gases of combustion then pass between the vertical header elements 30 and downwardly within the economizer 50 where

further quantities of heat are given up. From the lower part of the economizer 50 the gases pass upwardly through the air preheater 53 and are discharged in the well known manner to the stack. The steam generated in the water cooled walls of the combustion space 16 and the steam generated in the tubes 35 in the upward pass is discharged into the upper portion of the vertical header elements 30. Any water carried into the vertical header elements 30 by the steam falls by gravity from the steam and the steam passes upwardly in the vertical header elements 30 and through the pipes 36 to the superheater header 37, and therefrom through the superheater tubes 38 to the superheater header 39.

In the form of the invention illustrated in Figs. 1, 2 and 3, the steam demand is directly effective for causing positive downward circulation of the water within the vertical header elements 30, while in the form of the invention shown in Fig. 4, positive downward circulation of the water within the vertical headers 30 is effected by the pump 44, in accordance with the speed of the motor as controlled by steam demand or by the boiler attendant.

It will thus be seen that there is provided a steam generator embodying the utmost simplicity in construction with adequate provision for circulation in accordance with the steam demands, and with drums and the like rendered wholly unnecessary.

I claim:

1. In a steam generator, enclosing walls providing a combustion chamber, banks of tubes for lining said walls and for generating steam, a vertical baffle spaced from said combustion chamber to provide a pass for the gases from said combustion chamber, a plurality of spaced vertical header elements adjacent said baffle, the aforesaid banks of tubes being connected to said vertical header elements for discharging steam thereto and for receiving water therefrom, banks of steam generating tubes within said pass and extending from lower portions of said vertical header elements to upper portions thereof, and circulating means for inducing downward circulation of water in said vertical header elements.

2. In a steam generator, enclosing walls providing a combustion chamber, banks of tubes for lining said walls and for generating steam, a vertical baffle spaced from said combustion chamber to provide a pass for the gases from said combustion chamber, a plurality of spaced vertical header elements extending along said baffle, the aforesaid banks of wall tubes being connected to said vertical header elements for discharging steam thereto and for receiving water therefrom, banks of steam generating tubes within said pass and extending from lower portions of said vertical header elements to upper portions thereof, and circulating means responsive to the steam demand on the steam generator for inducing downward circulation of water in said vertical header elements.

3. In a steam generator, enclosing walls providing a combustion chamber, banks of tubes for lining said walls and for generating steam, a vertical baffle spaced from said combustion chamber to provide a pass for the gases from said combustion chamber, a plurality of spaced vertical header elements in said pass, the aforesaid banks of tubes being connected to said vertical header elements for discharging steam thereto and for receiving water therefrom, banks of steam generating tubes within said pass and extending

from lower portions of said vertical header elements to upper portions thereof, a superheater connected to said vertical header elements above the connections of said banks of tubes and circulating

5 means in said vertical header elements for maintaining downward circulation of water in said vertical header elements, said circulating means including steam driven motor members interposed between said superheater connections and said other connections and pump members operated thereby and disposed below said other connections.

4. In a drumless steam generator, enclosing walls providing a combustion chamber, banks of tubes for lining said walls and for generating steam, a plurality of spaced vertical header elements, a baffle extending along said vertical header elements, said vertical header elements and baffle being spaced from said combustion chamber to provide a pass for the gases from said combustion chamber, the aforesaid banks of tubes being connected to said vertical header elements for discharging steam thereto and for receiving water therefrom, and banks of steam generating tubes within said pass and extending from lower portions of said vertical header elements to upper portions thereof.

5. In a drumless steam generator, front, rear, top and side walls providing a combustion chamber, banks of tubes for lining certain of said walls and for generating steam, a baffle spaced from the rear wall of said combustion chamber to provide a pass for the gases from said combustion chamber, a plurality of spaced vertical header elements in said pass, the aforesaid banks of tubes being connected to said vertical header elements at the upper portions thereof for discharging steam thereto and being connected to said vertical header elements at the lower portions thereof for receiving water therefrom, and banks of steam generating tubes within said pass and extending from lower portions of said vertical header elements to upper portions thereof.

6. In a drumless steam generator, a top wall provided with burners, a front wall, side walls, and a bottom wall, banks of tubes for lining said walls and for generating steam, a rear wall for providing with said other walls a combustion chamber for the fuel supplied through said burners, a vertical baffle spaced from the rear wall of said combustion chamber to provide an upward pass for the gases from said combustion chamber, a plurality of spaced vertical header elements in said upward pass, the aforesaid banks of tubes being connected to said vertical header elements for discharging steam thereto at the upper portions thereof and for receiving water therefrom at the lower portions thereof, banks of steam generating tubes within said upward pass

55 and extending from lower portions of said vertical header elements to upper portions thereof, a superheater connected to said vertical header elements above the connections of said banks of tubes, and circulating means in said vertical header elements for maintaining downward circulation of water in said vertical header elements.

7. In a drumless steam generator a combustion chamber, banks of tubes for lining the walls of said combustion chamber and for generating steam, a baffle spaced from said combustion chamber, a plurality of spaced vertical header elements spaced from said combustion chamber and disposed along said baffle and providing with said baffle an upward pass for the gases from said

combustion chamber, the aforesaid banks of tubes being connected to said vertical header elements for discharging steam thereto and for receiving water therefrom, banks of steam generating tubes within said pass and extending from lower portions of said vertical header elements to upper portions thereof, a superheater connected to said vertical header elements above the connections of said banks of tubes, and circulating means in

said vertical header elements for maintaining downward circulation of water in said vertical header elements, said circulating means including steam driven motor members interposed between said superheater connections and said other connections and pump members driven thereby and disposed below said other connections.

JOHN PHILLIPS BADENHAUSEN.
